UNITED STATES PATENT OFFICE

SYLVESTER L. GOOKIN, OF QUINCY, MASSACHUSETTS, ASSIGNOR TO UNITED SHOE MANUFACTURING CORPORATION, OF PATERSON, NEW JERSEY, A CORPORATION OF NEW JERSEY

FASTENER-SETTING MACHINE

Application filed December 24, 1928. Serial No. 328,308.

This invention relates to fastener-setting machines and is herein illustrated as embodied in a machine for setting eyelets by upsetting and clenching their barrels.

In the manufacture of certain articles made of comparatively hard, rigid or non-compressible materials, as distinguished from leather and textile fabrics, there is a considerable demand for machines with which eyelets or grommets may be tightly clenched in such articles. For example, in the manufacture of radio-receiving apparatus some manufacturers use fasteners having tubular barrels to secure electrical contact members and other metallic conductors to sheets, plates or strips of comparatively hard, rigid or non-compressible insulating material such as bakelite and vulcanized rubber.

This class of work has heretofore been done with eyeleting machines in which two fastener-engaging tools have been caused to cooperate with pressure alone to upset and clench one end of the barrel of a fastener provided with a flange at its other end, but the results have not been uniformly satisfactory. A serious difficulty is that if the materials through which the fasteners extend are comparatively hard and non-compressible the clenched ends of the fasteners spring away from the articles of work when the clenching pressure of the tools is removed, so that the parts connected by the fasteners do not remain tight relatively one to another. If a very heavy clenching pressure is applied in an attempt to make the connection permanently tight it often results in breaking or cracking the insulating material through which the barrel of the fastener extends.

In view of the conditions above set forth an object of the present invention is to provide an improved machine by which the barrels of annular fasteners, such as eyelets or grommets, may be clenched tightly against comparatively hard, rigid or non-compressible materials without applying pressure so great as to break, crack or otherwise mutilate the articles of work or the fasteners clenched therein.

To this end a feature of the invention consists in a fastener-setting machine comprising two initially separated fastener-setting tools arranged to operate against opposite ends of the barrel of such a fastener, mechanism for relatively moving the tools one toward and from the other, and mechanism for rotating one of said tools continuously throughout the periods of upsetting and clenching pressure to supplement such pressure with a spinning action. It has been found in practice that when the barrel of a fastener is subjected to a spinning action during the period of the final or maximum clenching pressure, the clenched end of the barrel will remain tightly set instead of springing away from the work when the setting tools are separated. It has also been found that if the operating pressure is supplemented by a spinning action a moderate degree of pressure is sufficient to insure tight clenching.

In accordance with a feature of the invention, the illustrated machine is provided with a fastener-setting tool having a series of ribs formed and arranged to upset and clench the barrel of a tubular fastener with a spinning action. As herein illustrated this tool is provided with a central projection or pilot formed and arranged to project through a fastener-receiving hole previously formed in the fastener-receiving material, and the ribs above referred to merge into the base of this pilot and extend outwardly therefrom to flare one end of the fastener barrel with a spinning action and to continue this action until the flared end is clenched against the fastener-receiving material.

In the illustrated machine the spinning tool is mounted in a stationary horn detachably fixed to the frame of the machine so that horns provided with tools of various shapes and sizes may be readily substituted, one for another. Moreover, the illustrated horn is provided with transmission mechanism by which rotary motion may be communicated to the spinning tool. This transmission mechanism is enclosed in the horn and includes a shaft that projects lengthwise

through a shank portion of the horn and into an interior space in the frame of the machine so that when this shaft is connected to a driving train in the interior space the operator is protected from injury by the mechanism that furnishes rotation to the spinning tool.

Referring to the drawings,

Fig. 1 is a side elevation, partly broken away, of a fastener-setting machine in which the present invention is embodied;

Fig. 2 is a perspective view, partly in section, of the fastener-setting mechanism and includes a portion of a raceway for supplying fasteners thereto;

Fig. 3 is a vertical section showing the setting tools on a larger scale;

Fig. 4 is a horizontal section through the horn and the spinning tool and shows the transmission mechanism mounted in the horn;

Fig. 5 is a vertical section on an enlarged scale including the lower portion of one of the fastener-setting tools and a fastener carried thereby;

Fig. 6 is a bottom plan view of the tool illustrated in Fig. 5;

Fig. 7 is a top plan view of a preferred form of spinning tool formed in accordance with this invention;

Fig. 8 is a sectional development of the ribs and grooves embodied in the tool illustrated in Fig. 7; and

Fig. 9 is a sectional view of an article of manufacture comprising a plate of non-compressible insulating material and a metallic conductor fastened together by an eyelet clenched by the use of the machine illustrated in Fig. 1.

The general organization of the illustrated machine is similar in many respects to that illustrated and described in United States Letters Patent No. 1,369,021 granted February 22, 1921 on application of P. R. Glass. The frame 10 of the machine is hollow and is formed with an annular open base 12 and with an overhanging arm 14. A horizontal operating shaft 16 journaled in bearings in the frame is provided with a grooved cam 18 for operating a raceway 20, a pulley 22 for operating mechanism (hereinafter described) to supply fasteners to the raceway, and with a pulley 24 by which the shaft 16 may be driven. A clutch (not shown) is also mounted on the shaft 16 to be controlled by a rod 26 so that the pulley 24 may be coupled to the shaft by depressing the control rod and uncoupled when the control rod is raised by a spring 28. The pulley 24 is driven by a belt 30 that runs around a relatively small and continuously driven pulley 32 affixed to a countershaft 34 arranged below the frame 10. The pulleys 24 and 32 are preferably proportional to cause relatively slow rotation of the shaft 16.

The machine is provided with fastener-inserting mechanism comprising a vertical plunger 36 (Fig. 3), a fastener-inserting tool 38 carried thereby, a lever 40 for reciprocating the plunger, a link 42 for operating the lever 40 and a wrist pin 44 for operating the link to move the tool 38 to and from a fixed limit of operating movement. The wrist pin is carried by and projects from the cam member 18. The lever 40 is connected to the arm 14 by a fulcrum pin 46. Operating connection between the lever 40 and the plunger 36 is provided by a pair of links 48. The plunger 36 is arranged to slide in a bearing 50 formed in the arm 14. The clutch for coupling and uncoupling the pulley 24 and the shaft 16 may advantageously be of the type illustrated and described in United States Letters Patent No. 1,351,138 granted August 31, 1920 on application of R. B. Smith, the organization preferably being such that, as in the construction set forth in the Letters Patent last referred to, rotation of the shaft is arrested when the wrist pin 44 is at bottom center, as shown in Fig. 1, so that the fastener-inserting tool 38 will be raised to its highest position when the machine is at rest.

The raceway 20 is arranged between a pair of ears 52 formed on the arm 14 and is connected to the ears by a horizontal fulcrum pin 54. Mechanism is provided for oscillating the raceway about the pin 54 so that the lower end of the raceway will execute a substantially horizontal to-and-fro motion for the purpose of presenting fasteners to the inserting tool 38. The mechanism for this purpose comprises the aforesaid grooved cam 18, a lever 56 (Fig. 1), a cam roll 58 mounted on the lever, a horizontal rockshaft 60 to which the lever 56 is affixed, an arm 62 (Fig. 2) also affixed to the rockshaft, and a link 64 connecting the arm 62 and the raceway. The connection between the link and the raceway is formed by a pivot pin 66. This mechanism is so organized that when the inserting tool 38 is raised to its highest position, a fastener at the delivery end of the raceway will stand in register with the tool, but as the tool descends the raceway will be retracted from its path.

The delivery end of the raceway is provided with a spring-pressed detent 68 by which the leading fastener in the raceway is arrested so that it will register with the tool 38. In accordance with common practice the tool 38 is provided with a spring-pressed spindle 70 that normally projects therefrom to detach a fastener from the raceway and to carry the detached fastener to an article of work through which the barrel of the fastener is to be inserted. A compression spring 72 (Fig. 3) for normally projecting the spindle 70 is contained in a

socket bored in the lower end of the plunger 36.

Fasteners are fed into the upper end of the raceway 20 by a well-known form of mechanism comprising a hopper 74 carried by the raceway, a rotary brush (not shown) located in the hopper, a pulley 76 by which the brush is rotated, and a belt 78 by which rotation is transmitted from the pulley 22 to the pulley 76. The belt 78 runs over sheaves 80.

The fastener-inserting tool 38 cooperates with a rotary spinning and clenching tool 82 adjustably secured in a holder 84 (Fig. 15 3). This holder is cylindric but is provided with helical gear teeth 86 and with a narrow flange 88 at its lower end. A horn 90 is provided with a cylindric vertical socket 92 to provide a bearing for the holder 84.

20 The horn is detachably affixed to the frame 10 and for this purpose the frame is provided with a cylindric socket 92 open at its front end to receive a cylindric shank 94 formed on the horn, and open at 25 its rear end to provide communication with the interior space in the frame 10. A set-screw 96 screwed into the frame 10 is arranged to engage the shank 94 to fasten the horn rigidly to the frame. A dowel 98 30 (Fig. 1) projects into the frame 10 and into a portion of the horn to prevent the horn from turning about the axis of the shank 94 and to maintain the axis of the spinning tool 82 parallel to that of the fastener-inserting tool 38. A face 100 formed 35 on the horn is arranged to abut against a front face of the frame 10 to register the spinning tool relatively to the fastener-inserting tool 38. A broken line A in Fig. 40 4 indicates the axis of the cylindric shank 94, and it may be observed that this line intersects the axis of the tool 82.

The horn 90 is also provided with transmission mechanism by which rotation may 45 be imparted to the tool holder 84. This mechanism comprises a shaft 102 one portion of which is journaled in the shank 94 and another portion of which is journaled in a bushing 104 inserted into the horn. A 50 helical gear 106 formed on or affixed to the forward end of this shaft meshes with the helical teeth 86 to drive the tool holder 84. After the shank 94 of the horn has been 55 inserted into its socket 92 in the frame 10 a pulley 108, inserted through the base 12 into the interior space of the frame 10, is affixed to the rear end of the shaft 102, the pulley being provided with a set-screw 110 60 for this purpose. A belt 112 (Fig. 1) runs over the pulley 108 and around a pulley 114 on the countershaft 34, the spinning tool 82 being thereby rotated continuously so long as driving power is applied to the counter- 65 shaft. The belts and pulleys, as shown,

cause the spinning tool to rotate about eight turns while the shaft 16 is turning once.

The horn 90 is designed to provide for inserting the transmission shaft 102 from front to rear, and when these parts have 70 been assembled they are maintained in co-operative relation by a screw plug 116 screwed into the forward end of a bushing 118 pressed tightly into the horn and forming a chamber for the gear 106. The plug 75 116 also excludes dirt from the gear chamber and prevents lubricating oil from running out. Moreover, when the shaft 102 is driven in the direction indicated by an arrow in Fig. 4 the plug 116 sustains the end 80 thrust due to the reaction of the helical gear teeth.

The tool holder 84 is inserted upwardly 85 into the socket 92 before the shaft 102 and gear 106 are inserted into the horn. The flange 88 at the lower end of the holder 84 90 engages the horn to prevent the holder from being inserted too far, and the holder is confined in its socket by a screw plug 120 screwed upwardly into the bottom of the horn. This plug prevents lubricating oil 95 from running out of the socket 92. A hardened steel shim 122 of suitable thickness is interposed between the bottom of the holder 84 and the plug 120 to sustain the downward pressure of the holder and to eliminate axial play thereof. The direction of rotation of the gear 106 maintains a constant downward pressure against the gear teeth 6. 100

The holder 84 is bored and tapped to provide a concentric socket to receive the shank 124 of the spinning tool 82, the lower portion of the tool being provided with a left-hand thread 126 to cooperate with a complementary internal screw-thread tapped in the holder. This screw-thread connection provides for vertical adjustment of the spinning tool in accordance with the thickness of the articles of work to which fasteners 110 are to be applied. The upper portion of the tool 82 is also provided with a left-hand screw thread 128 to cooperate with a retaining nut 130. The bottom of this nut is seated on the upper end of the holder 84. The direction of rotation of the holder 84 tends 115 to tighten the spinning tool and the nut 130, but if it were preferred to drive the spinning tool in the opposite direction the above-mentioned tightening effect would be obtained by substituting right-hand threads 120 for the left-hand screw threads 126 and 128.

To insure tight clenching of fastener barrels against non-compressible articles of work without using a heavy pressure the 125 spinning tool, 82 illustrated in Figs. 2, 7 and 8, is provided with a circular series of metal-working formations represented as ribs 132 separated by depressions, the ribs 132 being nearly but preferably not quite radial with 126

respect to the axis of the tool and having smooth, blunt fastener-engaging surfaces. The preferred profile of these ribs is shown best by the sectional development in Fig. 8 in which an arrow indicates the direction in which the ribs move. The profiles of the ribs are like those of ratchet teeth to provide inclined working faces 134 that will run around on the barrel of a fastener without applying much rotational effort to the barrel. The spinning tool is also provided with a central tapering projection or pilot 136 into which the ribs 132 merge. The slight skewing of the ribs from strictly radial relation to their axis of rotation produces a component of outward deflection of the metal brought to bear against them. This component of deflection facilitates the upsetting by working the metal of the barrel outwardly with a flaring effect. In practice, the quantity of metal worked outwardly is sufficient to avoid splitting the metal.

Fig. 9 illustrates a typical example of an eyelet that has been inserted through two hard and non-compressible elements and clenched by a spinning tool formed in accordance with this invention. The numeral 138 indicates a plate of bakelite and numeral 139 indicates a brass or copper contact plate. The eyelet comprises an unscored tubular barrel 140 and a flange 142 of ductile metal such as brass, one end 144 of the barrel being turned outwardly and backwardly toward the flange and clenched tightly against the bottom surface of the element 138 without being flattened or split.

To insure the most satisfactory spinning action by the tool 82 it is necessary to prevent rotation of the eyelet. For this reason the tool 38 is provided with formations designed to grip the flanged end of the eyelet so that the latter will not be turned by the rotational movement of the spinning tool. Referring to Figs. 5 and 6, the lower face of the tool 38 is provided with an annular depression 146 to receive the flange 142 of the eyelet. The inner boundary of this depression is formed by an annular protruding lip or flange 148 having a tapering formation that enters slightly into the eyelet at the junction of the barrel 140 and the flange 142. Thus, when pressure is applied to the eyelet by downward thrust of the tool 38 the flange 148 becomes wedged tightly in the upper end of the eyelet and exercises a considerable gripping action. The holding effect of the flange 148 may be supplemented by grooves scored in the depression 146. As shown in Fig. 6 radial grooves 150 are scored not only in the depression 146 but also in the flange 148 and in the protruding margin 152 of the tool.

The described machine operates in the following manner to insert an eyelet and to

clench the eyelet with a spinning action. It is to be assumed that the articles 138 and 139 of work have previously been provided with holes to receive the barrel of the eyelet and that the operator has placed the articles on the spinning tool 82 so that the pilot portion 136 projects through the holes to maintain them in register with each other and with the eyelet centered by the spindle 70. When the machine is connected to a source of power such as the continuously driven countershaft 34 the driving pulley 34 and the spinning tool 82 will rotate continuously not only while the operating shaft 16 is being driven but also while it is unclutched and stationary.

The initial position of the wrist pin 44 is illustrated in Fig. 1 and the initial positions of the inserting tool 38 and the raceway 20 are illustrated in Fig. 2. Thus, when the operator depresses the clutch-controlling rod 26 to start the machine the tool 38 is fully raised and the raceway 20 supports a fastener in register with the spindle 70. During the first stages of downward movement of the plunger 36 the spindle 70 is inserted into the barrel 140 of the fastener then lying against the spring-pressed detent 68 at the delivery end of the raceway. During this inserting movement of the spindle 70 the raceway 20 is retracted from the path of the tool 38, the fastener being thereby detached from the raceway. The detached fastener clings to the spindle 70, the lower portion of the spindle being slightly tapered to insure a snug fit in the barrel 140 as shown in Fig. 5.

Further downward movement of the plunger 36 carries the tip of the spindle 70 into engagement with the tip of the pilot portion 136 by which the spindle is arrested. The downward movement of the plunger 36 continues, thereby causing the tool 38 to bear upon the flange 142 of the fastener and to depress the barrel 140 of the fastener through the holes in the elements 138 and 139 of the work. As the lower end of the barrel 140 passes through these elements it is slightly expanded by the tapering pilot 136 and thereby maintained in concentric relation to the axis of the spinning tool. As shown in Figs. 2 and 3 the base of the pilot portion 136 curves outwardly, this formation causing a gradual flaring of the barrel. At this stage the spinning effect of the ribs 132 begins, and the downward movement of the tool 38 is relatively slow and undergoing deceleration because the wrist pin 44 is approaching a "dead center". Thus, the spinning action increases gradually in relation to the speed with which the flaring and upsetting of the barrel progresses. During the remainder of the downward movement of the inserting tool 38 the lower end of the barrel 140 is

subjected to the spinning action of the ribs 132 which turn it back while working the metal away from the center with the result that a crowned clenched formation 144 (Fig. 9) is imparted to the barrel without causing the barrel to split at any point. The ribs 132 so greatly facilitate the upsetting and clenching that no great pressure is required to effect a tight clench. Moreover, since the 5 spinning action continues throughout the period of maximum clenching pressure the spinning tool imparts a permanent "set" to the clenched portion 144 so that the latter will not spring back when the clenching 10 pressure is relieved. This result is particularly advantageous in certain kinds of work, for example, clenching eyelets in articles made of bakelite, vulcanized rubber and other rigid materials used extensively in radio construction since, in work of this kind, it is necessary not only to make all mechanical connections quite tight but also to avoid cracking and chipping the brittle materials to which electrical conductors and fasteners 15 are applied.

In practice the operator will release the control rod 26 without delay after starting the operation of the machine, so that the wrist pin 44 will execute only one cycle before stopping. During the latter stages of the upward movement of the inserting tool 38 the delivery end of the raceway 20 will return to its initial position to present another fastener in register with the spindle 20 35 70.

It is to be observed that the mechanism for driving the spinning tool 82 is arranged so that it does not encumber in any degree the space required for manipulation of the 40 articles of work, and that this mechanism is fully enclosed so that neither the articles of work nor the operator's hands or clothing can be caught thereby. With the exception of the pulley 108, Figs. 1 and 4, the transmission mechanism for driving the spinning tool is fully enclosed in the horn 90, the pulley itself being enclosed in the hollow frame 10 which is open at the bottom to provide for placing the belt 112 on that 45 50 55 pulley.

When the machine is to be used for operating on work that requires another type of tool instead of the spinning tool 82 or a different type or shape of horn instead of the horn 90 the exchange may be readily made by detaching the pulley 108 and releasing the horn, the set-screws 96 and 110 being the only parts that require the use of a tool to accomplish the change.

Having thus described my invention, what I claim as new and desire to secure by Letters Patent of the United States is:

1. A fastener-setting machine comprising two initially separated fastener-setting tools 45 formed and arranged to project into and

operate against opposite ends of the barrel of a tubular fastener, automatic mechanism for relatively moving said tools to apply upsetting and clenching pressure against the ends of the barrel of a fastener, and mechanism for rotating one of said tools continuously throughout a period of upsetting and clenching pressure to supplement such pressure with a spinning action. 70

2. A fastener-setting machine comprising two initially separated fastener-setting tools formed and arranged to project into and operate against opposite ends of the barrel of a tubular fastener, mechanism for relatively moving said tools to apply upsetting and clenching pressure, and mechanism for rotating one of said tools continuously throughout a period of upsetting and clenching pressure to supplement such pressure with a spinning action, the other one of said tools being provided with means formed to fit tightly in the barrel of a fastener for preventing rotation of the fastener during 80 85 90 said period.

3. A fastener-setting machine comprising an axially movable tool and a rotary tool initially separated and arranged to operate against opposite ends of the barrel of a tubular fastener, automatic mechanism arranged to advance said axially movable tool to a 95 fixed limit of operative movement to apply upsetting pressure axially against the ends of the fastener, and mechanism arranged to rotate said rotary tool prior to and during the period of maximum pressure applied by 100 the other tool, the rotary tool having a fastener-centering formation and another formation to upset and clench the barrel of the fastener.

4. A fastener-setting machine comprising a rotary setting tool and a non-rotary setting tool coaxially related and arranged to operate against opposite ends of the barrel of a tubular fastener, means arranged to present a fastener to one of said tools, automatic mechanism arranged to operate said non-rotary tool to thrust a fastener axially into an article of work and against the other one of said tools with upsetting and clenching pressure, and mechanism arranged to 105 110 115 rotate said rotary tool throughout the upsetting and clenching period, said rotary tool having a protruding metal-working element formed to set the clenched portion of the barrel with a spinning action, and the 120 non-rotary tool having a formation to grip the fastener and prevent rotation thereof.

5. A fastener-setting machine comprising a non-rotary setting tool and a rotary setting tool arranged to operate against opposite ends of the barrel of a tubular fastener, mechanism arranged to operate one of said tools to thrust a fastener axially against the other one of said tools with upsetting and clenching pressure, and mechanism arranged 125 130 135

to rotate said rotary tool during the upsetting and clenching period, said non-rotary tool having a formation to prevent rotation of the fastener and said rotary tool having 5 a skewed metal-working formation arranged to upset and clench the barrel of the fastener with a spinning action.

6. A fastener-setting machine comprising a non-rotary setting tool and a rotary setting tool arranged to operate against opposite ends of the barrel of a tubular fastener, mechanism arranged to operate one of said tools to thrust a fastener axially against the other one of said tools with upsetting pressure, and mechanism arranged to rotate said rotary tool during the upsetting and clenching period, said non-rotary tool having a scored tapering formation of a size to enter and grip one end of the barrel and thereby 15 prevent rotation of the fastener, and said rotary tool having a metal-working formation to upset and clench the barrel with a spinning action.

7. A fastener-setting machine comprising 25 a non-rotary setting tool and a rotary setting tool arranged to operate against opposite ends of the barrel of a tubular fastener, mechanism arranged to reciprocate one of said tools axially to apply upsetting pressure to the fastener, and mechanism arranged to rotate said rotary tool, said non-rotary tool having a scored fastener-engaging surface to prevent rotation of the fastener, and said rotary tool having a formation 30 to upset and clench the barrel with a spinning action.

8. A fastener-setting machine comprising a non-rotary setting tool and a rotary setting tool formed and arranged to project 40 into and operate against opposite ends of the barrel of a tubular fastener, mechanism arranged to reciprocate one of said tools axially to apply upsetting pressure to the fastener, and mechanism arranged to rotate 45 said rotary tool, said non-rotary tool having means to grip the fastener and thereby prevent rotation thereof, and said rotary tool having a circular series of inclined metal-working faces to upset and clench the barrel with a spinning action.

9. A fastener-setting machine comprising a non-rotary setting tool and a rotary setting tool formed and arranged to project into and operate against opposite ends of 55 the barrel of a tubular fastener, mechanism arranged to reciprocate one of said tools axially to apply upsetting pressure to the fastener, and mechanism arranged to rotate said rotary tool, said non-rotary tool having a formation to grip the fastener and thereby prevent rotation thereof, and said rotary tool having one or more non-radial metal-working ribs formed to upset and clench the barrel with a spinning action.

65. 10. A fastener-setting machine comprising

a non-rotary setting tool and a rotary setting tool arranged to operate against opposite ends of the barrel of a tubular fastener, mechanism arranged to reciprocate one of said tools axially to apply upsetting pressure to the fastener, and mechanism arranged to rotate said rotary tool, said non-rotary tool having a formation to grip the fastener and thereby prevent rotation thereof, and said rotary tool having one or more non-radial metal-working elements formed to upset and clench the barrel with a spinning action and with a component of outward radial deflection.

11. A fastener-setting machine comprising 70 a non-rotary setting tool and a rotary setting tool arranged to operate against opposite ends of the barrel of a tubular fastener, mechanism arranged to reciprocate one of said tools axially to apply upsetting pressure to the fastener, and mechanism arranged to rotate said rotary tool, said non-rotary tool having a formation to grip the fastener and thereby prevent rotation thereof, and said rotary tool having a projecting fastener-engaging pilot and a series of metal-working ribs merging into said pilot and formed to upset and clench the barrel with a spinning action.

12. A fastener-setting machine comprising 75 a non-rotary setting tool and a rotary setting tool arranged to operate against opposite ends of the barrel of a tubular fastener, mechanism arranged to reciprocate one of said tools axially to apply upsetting pressure 80 to the fastener, and mechanism arranged to rotate said rotary tool, said non-rotary tool having a formation to grip the fastener and thereby prevent rotation thereof, and said rotary tool having a fastener-engaging pilot 85 and one or more metal-working ribs skewed from radial relation but merging into said pilot and formed to upset and clench the barrel with a spinning action.

13. A fastener-setting machine comprising 90 a non-rotary setting tool and a rotary setting tool arranged to operate against opposite ends of the barrel of a tubular fastener, mechanism arranged to reciprocate one of said tools axially to apply upsetting pressure 95 to the fastener, and mechanism arranged to rotate said rotary tool, said non-rotary tool having a formation to grip the fastener, and thereby prevent rotation thereof, and said rotary tool having a series of metal-working ribs of ratchet-shaped profile 100 formed and arranged to upset and clench the barrel with a spinning action.

14. A fastener-inserting machine comprising 105 an axially movable fastener-inserting tool and a rotary tool formed and arranged to operate against opposite ends of the barrel of a tubular fastener, means arranged to supply fasteners to said axially movable tool, mechanism arranged to operate said axially 110

movable tool to transfer a fastener from said supplying means and press the fastener against said rotary tool, and mechanism arranged to rotate said rotary tool, the rotary tool having a metal-working formation to upset and clench the barrel of the fastener with a spinning action.

15. A fastener-inserting machine comprising an axially movable fastener-inserting tool and a rotary tool formed and arranged to operate against opposite ends of the barrel of a tubular fastener, means arranged to supply fasteners to said axially movable tool, mechanism arranged to operate said axially movable tool to transfer a fastener from said supply means and press the fastener against said rotary tool, and mechanism arranged to rotate said rotary tool, said axially movable tool having an interrupted fastener-engaging surface to prevent rotation of the fastener and said rotary tool having a metal-working formation to upset and clench the barrel of the fastener with a spinning action.

20. 16. A fastener-inserting machine comprising an axially movable fastener-inserting tool and a rotary tool arranged to operate against opposite ends of the barrel of a tubular fastener, means arranged to supply fasteners to said axially movable tool, mechanism arranged to operate said axially movable tool to transfer a fastener from said supplying means and press the fastener against said rotary tool, and mechanism arranged to rotate said rotary tool, said rotary tool having one or more metal-working ribs formed and arranged to upset and clench the barrel with a spinning action and also having a central pilot to maintain the barrel of the fastener in concentric relation to the axis of the spinning tool.

25. 17. A fastener-setting machine comprising clutch-controlled fastener-setting mechanism including an axially movable setting tool formed and arranged to operate against one end of the barrel of a tubular fastener, a rotary tool formed and arranged to operate against the opposite end of the barrel, automatic means for relatively moving said tools to apply upsetting and clenching pressure to the fastener, and mechanism for rotating said rotary tool continuously, said rotary tool having a central work-engaging pilot and a metal-working formation to upset and clench the barrel with a spinning action.

30. 18. A fastener-inserting machine comprising a frame, an axially movable tool and a rotary tool arranged to operate against opposite ends of a fastener, mechanism arranged to operate said axially movable tool to apply upsetting and clenching pressure to a fastener, a horn in which said rotary tool is mounted, said horn having a shank portion and said frame having a socket to re-

ceive said portion and thereby support the horn, and transmission mechanism enclosed in said horn to communicate rotation to said rotary tool, an element of said transmission mechanism extending through said shank portion of the horn and projecting from the inner end thereof to be operatively connected with a source of rotation.

35. 19. A fastener-setting machine comprising a hollow frame provided with a socket extending through a wall thereof, a horn provided with a shank formed to be inserted into said socket, a rotary spinning tool mounted in said horn, transmission mechanism enclosed in said horn to communicate rotary motion to said tool, said transmission mechanism including a shaft extending through and projecting from the inner end of said shank portion, driving means arranged to communicate rotation to said shaft inside said hollow frame, and mechanism arranged to cooperate with said spinning tool to upset and clench a fastener.

40. 20. A spinning tool provided with a central pilot projecting therefrom to engage the internal surface of a tubular fastener of ductile metal, and with a circular series of ribs having smooth blunt operating surfaces formed to upset and clench the fastener, said ribs being skewed from radial positions to work the metal of the fastener outwardly in consequence of relatively rotating the tool and the fastener.

45. 21. A spinning tool provided with a central pilot to engage the internal surface of a tubular fastener of ductile metal, and with a circular series of ribs having smooth operating surfaces formed to turn back and clench the fastener with a spinning action.

50. 22. A spinning tool provided with a central pilot to engage the internal surface of a tubular fastener of ductile metal, and with a circular series of ribs having smooth operating surfaces formed to upset and clench the fastener, said ribs having ratchet-shaped profiles and being skewed from radial positions to work the metal of the fastener outwardly in consequence of relatively rotating the tool and the fastener.

55. In testimony whereof I have signed my name to this specification.

SYLVESTER L. GOOKIN.
